Fig. 2

FIG. 1 is an elevational view of a bottle or similar article embodying my new design, in which the essential features thereof are two cylindrical sections, at the bottom and near the top of the bottle or similar article, such sections being peripherally rounded at their ends and being connected by a cylindrical portion of lesser diameter, on which is a multiplicity of longitudinally extending thin rounded ribs spaced apart a distance which is approximately the thickness of the ribs and which terminate in rounded ends, short of the ends of the connecting cylindrical portion of the bottle or similar article as shown; and

FIG. 2 is a top plan view thereof.

I claim:

The ornamental design for a bottle or similar article, as shown and described.
